(57) **CLAIM**

The ornamental design for an optical parameter measuring instrument, as shown and described.

DESCRIPTION

FIG. 1 is a front perspective view of an optical parameter measuring instrument in accordance with the invention; FIG. 2 is a front view of the optical parameter measuring instrument shown in FIG. 1; FIG. 3 is a rear view of the optical parameter measuring instrument shown in FIG. 1; FIG. 4 is a right side view of the optical parameter measuring instrument shown in FIG. 1; FIG. 5 is a left side view of the optical parameter measuring instrument shown in FIG. 1; FIG. 6 is a top view of the optical parameter measuring instrument shown in FIG. 1; FIG. 7 is a bottom view of the optical parameter measuring instrument shown in FIG. 1; and, FIG. 8 is a rear perspective view of the optical parameter measuring instrument shown in FIG. 1.
